Fig. 2

Fig. 3

Fig. 4

FIGURE 1 is a perspective view of a combined closed circuit television transmitter and receiver cabinet showing my new design;

FIG. 2 is a front elevational view of the cabinet and housing illustrated in FIG. 1;

FIG. 3 is a top plan view of the cabinet and housing shown in FIGS. 1 and 2; and

FIG. 4 is a side elevational view showing the side opposite that seen in FIG. 1.

The back of the unit is conventionally plain. The dominant features of my design reside in the portions shown in full lines in the drawings.

I claim:

The ornamental design for a combined closed circuit television transmitter and receiver cabinet, as shown and described.
